CHARLES C. KENYON, OF SOMERVILLE, NEW JERSEY

TENTERING AND DRYING MACHINE

Application filed December 28, 1929. Serial No. 417,121.

This invention relates to tentering and drying machines.

One object of the invention is to provide a device of the character described including a wall or baffle arrangement having improved means associated with relatively movable parts to effect a closure for the prevention of substantial air leakage while permitting the movement of said parts.

10 Another object of the invention is the provision of a device of the nature set forth having means for moving materials of varying widths through a casing in which air circulation is assured by a baffle means, the latter 15 having a closure movable according to the width of the material for which the device is set to permit the air to flow along the layers of material but with a minimum of air leakage.

20 Another object of the invention is to furnish a device of the type mentioned in which the closure means is constructed to operate within the ordinary dimensions of the machine, while permitting the latter to receive 25 materials over a wide range of widths.

A further object of the invention is to construct a machine of the class alluded to in which the closure means coacts in an improved manner with the layers of material 30 and also with the vertical adjustment bars for width; and in which the construction is simple, compact, rugged, relatively inexpensive to manufacture and assemble, operative automatically with the adjustment of the machine, 35 and reliable and efficient to a high degree in use.

Other objects and advantages of the invention will become apparent as the specification proceeds.

40 With the aforesaid objects in view, the invention consists in the novel combinations and arrangements of parts hereinafter described in their preferred embodiments, pointed out in the subjoined claims, and illustrated on the annexed drawing, wherein like parts are designated by the same reference characters throughout the several views.

In the drawing:

Figure 1 is an internal top view of a device embodying the invention.

Fig. 2 is a view in side elevation of the same with parts removed to show internal construction.

Fig. 3 is an enlarged vertical sectional view of a closure means, taken on line 3-3 of Fig. 4.

Fig. 4 is a view in vertical section of the same taken on line 4-4 of Fig. 3.

Fig. 5 is a bottom sectional view taken on line 5-5 of Fig. 4.

Fig. 6 is a vertical sectional view taken on line 6-6 of Fig. 5.

The advantages of the invention as here outlined are best realized when all of its features and instrumentalities are combined in one and the same structure, but, useful devices may be produced embodying less than the whole.

It will be obvious to those skilled in the art to which this invention appertains, that the same may be incorporated in several different constructions. The accompanying drawing, therefore, is submitted merely as showing the preferred exemplification of the invention.

Generally described, the invention provides a tentering and drying machine having baffle means for causing a flow of air along any predetermined path. The machine includes elements extending through the baffle means, said elements being movable in adjusting the machine for operation or according to the width of the material to be dried thereby. To permit movement of the said elements, the baffle means has openings of the requisite size, these being closed by a novel closure means. The latter is movable with the adjustment of the elements and permits the full movement of the elements while maintaining said openings against an undesired flow of air therethrough. Among the elements may be mentioned the vertically screw adjusted bars for moving the chain tracks, and also the material that is being dried. The dimension between the said bars varies as does also the dimension between the walls of the casing and the said bars. The closure means is operative at both locations, and without necessitating any increase in the width of the machine. The closure means may take various

forms although herein shown as consisting of substantially flat, relatively movable plates. To prevent the material from impinging the baffle means, a suitable guide means is provided therefor. The general arrangement of the baffles, blowers and heating means is claimed in my application Serial No. 417,120, filed Dec. 28, 1929.

Referring in detail to the drawing, 10 denotes a device embodying the invention. The same includes an elongated casing 11 having a top 12, side walls 13 and front and rear end walls 14, 15. Mounted horizontally in the casing are a plurality of telescopic vertically spaced rollers 16 adjacent to each end of the machine. Associated with the rollers are tracks 17 for any suitable chains carrying the usual hooks with which the material is engaged. These tracks are mounted on vertical bars 18 for adjustment toward or away from each other, the said bars being movable by the screw bars 19 having the usual left-hand, right-hand threads. The material 20 enters the casing at 21 and passes downward through the machine in a series of spaced layers and leaves the casing at the bottom thereof at 22.

Dividing the casing into a plurality of sections are any suitable wall or baffle means which is constructed to cause the air in the casing to flow along any predetermined paths, or to prevent a flow of air into certain portions of the machine, or leakage thereof, according to the purpose or construction of the same or the machine. Thus a baffle 23 divides the casing into a plurality of superimposed drying compartments 24, 25. An auxiliary baffle 26 forms a cooling passage 27 along the bottom of the casing. The material 20 passes in layers through the drying compartments 24, 25 and hence out through the cooling passage 27. The latter may also be thought of as a compartment for the treatment of the material.

45 To blow air through the casing for drying the material, any suitable source of air under pressure is utilized. This may include one or more blowers located as desired, for example, in the casing 11. The blower means comprises in one embodiment of the invention, blowers 28, 29 positioned at opposite ends of the casing and communicating with the respective drying compartments 24, 25. These blowers may be mounted in vertical end walls 30, 31 for the said compartments. The blower 28 constitutes an inlet and circulatory blower, since it draws in air through the passage 27, discharges the air according to arrow *a*, the circulation blower 29 receiving and discharging the air as shown by arrow *b*, and the blower 28 recirculating the air as shown by arrow *c*. Each of the said blowers steps up the pressure of the air received from the other blower, to overcome the pressure drop of the air along the said layers, and to

cause an efficient circulation at a low average pressure, with a minimum expenditure of power. An outlet blower 32 ejects a portion of the moist air to maintain a predetermined condition of the circulating air.

To heat the air, any suitable means may be used located in any desirable position. For instance, the steam coils 33 may be positioned between the layers of material, and the heat supplied thereby controlled as may be feasible.

To confine the air substantially to the spaces between the layers, side baffles 34 may be provided at the sides of the casing, the arrangement being such as to afford the necessary space at the said sides for the members 18 and 19. These baffles terminate in spaced relation to the ends of the layers of material, and are of angular form at their ends 35 for an easy entrance of air laterally into those alternate spaces between the layers which are otherwise closed by the rollers 16. The auxiliary baffles are preferably removably mounted and extend substantially end to end, but with their inner ends 36 in spaced relation to each other.

To cause the baffles 23 and 26 to enclose the moving material 20 and the vertical bars 18 for every adjustment or width of material, the said baffles are formed with the closure means that will now be described.

At each point 37 where a bar 18 extends through a baffle 23 or 26, an opening 38 is provided in said baffle, which opening may be constructed in any suitable manner, as a slot in the baffle, or by making the baffle of spaced plates 39, 40. Secured to each vertical bar 18 is a slide plate 41 extending toward the center of the machine where they overlap at 42. These slide plates lie parallel to the baffle plates, and overlie the edge 43 thereof and may move relatively closely therealong. The said slide plates can be fastened to the vertical bars 18 in any suitable manner as, for instance, by angle brackets 44.

It will be understood that when the vertical bars 18 are as far apart as they can be, the slide plates 41 still overlap, while when the said bars are moved toward each other into their position of relatively closest proximity, the space for the overlap will nevertheless be sufficient. Thus that portion of the opening 38 between the bars 18 is permanently closed in any position of the bars.

Closing the opening 38 between the vertical bars 18 and the sides of the casing, is a closure means consisting of a plurality of telescopically coacting plates of any desired number. To provide for a maximum of adjustability a unit 45 of preferably three short plates is used at each side of the machine. Each of these units includes a plate 46 secured to a bar 18 in any suitable manner, as by a bracket 47. This plate 46 may coact in any desired manner with a plate 41, and the side edges of

both may form continuous lines. The closure plate 46 may terminate in a transverse lip 48 at the end thereof remote from its bar 18.

Positioned on the opposite side of the baffle 5 is a relatively stationary plate 49 which may be co-ordinated with the former in any desired manner, and may be fixedly mounted on the side walls of the casing at 50. The plate 49 may be spaced from its baffle, and has a lip 51 at its free end extending toward the same.

Positioned between the plates 46 and 49 is an intermediate plate 52 having lips 53, 54 co-acting respectively with the lips 48 and 51. The intermediate plates may be supported in extended position by lugs 55.

The operation of the units 45 will now be clearly apparent. When the vertical bars 18 move toward each other, both of the closure units 45 expand, the lips 48, 53 interengaging

20 for movement of the intermediate plate, and the lips 51, 54 engaging to limit the said movement. When the movement of the bars 18 is reversed, the closure units are caused to collapse in an obvious manner.

25 The slight open spaces that may be observed will cause no material air leakage. Wherever desired, however, these may be suitably closed.

For enclosing the material 20, a somewhat similar closure means may be used as that hereinbefore described. As the closure means must extend at an angle to the material, the baffles 23 and 26 are formed with offsets 56, 57 providing the substantially vertical wall portions 58. In each of the latter is formed an opening or slot 59 of any suitable shape, or rectangular as shown. Plates 60 overlapping in the center of the machine at 60a extend over the said opening in relative proximity to the baffles. The plates 60 have longitudinal central openings 61 which are comparatively narrow, but of the proper width for the passage of the material. The said openings have enlarged ends 62 for accommodating the chains. It will be appreciated that the plates 60, may each consist of one or more parts fabricated together. They may be fixed to the chain guides at 63.

To close the openings 59 adjacent to the sides of the machine, telescopic units 64 are provided, each comprising preferably three plates. The plate 65 is mounted to move with the plate 60, and may be secured thereto, or of integral construction therewith. The plate 65 terminates in a transverse engagement portion or lip 66.

Disposed on the opposite side of the vertical wall portion 58 is a plate 67 mounted in any desired manner as, for example, at 68. This plate extends inward forming a closed guide recess 69, and terminating at its end in a lip 70 entering the opening 59. An intermediate plate 71 is positioned between the plates 65 and 67, and has end lips 72, 73 engageable respectively with the lips 70 and 66 in the

manner hereinbefore set forth. The lip 72 moves in the guide recess, and the arrangement shown is compact and of minimum thickness. The intermediate plate may be retained in slidable position by any suitable 70 guide means, such as the lugs 55 described, if that should be necessary.

To act as a guide the material 20, and particularly to prevent an end of the same from catching at a baffle 23 or 26, at the narrow 75 openings 61, a guide element 74 is provided. This is made of a non-corrosive metal, such as Monel metal. It is preferably stationary, and sufficiently spaced from the chains to avoid interference with the setting of the 80 machine for materials of varying widths. The baffle is inclined at any suitable angle and its upper end is substantially at the center line of an opening 59.

It will be understood that the details of 85 construction may be changed considerably within the principles of the invention, and that the drawing is submitted in an illustrative and not in a limiting sense.

I claim:

1. A tenting and drying machine including a casing, means therein supporting a material in a plurality of spaced layers, said means including carrier bars in proximity to opposite walls of the casing, said bars being movable toward or away from each other for adjustment of the supporting means for materials of varying widths, baffle means dividing the casing into a plurality of compartments each of which contains a plurality of the layers, means to feed air through the compartments and along the layers, said baffle means having openings for the carrier bars and other openings for the movement of the material from one to another of the 100 compartments, and telescopic closure means 105 between the casing walls and the carrier bars to adjust said openings according to the width of the material to prevent unintended flow of air through the openings. 110

2. A tenting and drying machine including a casing, means therein supporting a material in a plurality of spaced layers, said means including carrier bars in proximity to opposite walls of the casing, said bars being movable toward or away from each other for adjustment of the supporting means for materials of varying widths, baffle means dividing the casing into a plurality of compartments each of which contains a plurality of the layers, means to feed air through the compartments and along the layers, said baffle means having openings for the carrier bars and other openings for the movement of the material from one to another of the compartments, and adjustable closure means between the closure bars to act as a closure for said openings according to the width of the material to prevent substantial leakage therethrough. 125 130

3. A tentering and drying machine including a casing, means therein supporting a material in a plurality of spaced layers, said means including carrier bars in proximity to opposite walls of the casing, said bars being movable toward or away from each other for adjustment of the supporting means for materials of varying widths, baffle means dividing the casing into a plurality of compartments each of which contains a plurality of the layers, means to feed air through the compartments and along the layers, said baffle means having openings for the carrier bars and other openings for the movement of the material from one to another of the compartments, and relatively slidable plates between the bars and also between the casing walls and the bars to close the said openings according to the width of the material to avoid unintended flow of air through the same.
4. A tentering and drying machine including a casing, means therein supporting a material in a plurality of spaced layers, said means including carrier bars in proximity to opposite walls of the casing, said bars being movable toward or away from each other for adjustment of the supporting means for materials of varying widths, baffle means dividing the casing into a plurality of compartments each of which contains a plurality of the layers, means to feed air through the compartments and along the layers, said baffle means having openings for the carrier bars and other openings for the movement of the material from one to another of the compartments, and relatively slidable plates between the bars and also between the casing walls and the bars to close the said openings according to the width of the material to avoid unintended flow of air through the same, said plates being connected for movement with the material supporting means.
5. A tentering and drying machine including a casing, means therein supporting a material in a plurality of spaced layers, said means including carrier bars in proximity to opposite walls of the casing, said bars being movable toward or away from each other for adjustment of the supporting means for materials of varying widths, baffle means dividing the casing into a plurality of compartments each of which contains a plurality of the layers, means to feed air through the compartments and along the layers, said baffle means having openings for the carrier bars and other openings for the movement of the material from one to another of the compartments, and relatively slidable plates between the bars and also between the casing walls and the bars to close the said openings according to the width of the material to avoid unintended flow of air through the same, the slid-able plates for the opening for the material being on opposite sides thereof to narrow said opening.

6. A tentering and drying machine including a casing, means therein supporting a material in a plurality of spaced layers, said means including carrier bars in proximity to opposite walls of the casing, said bars being movable toward or away from each other for adjustment of the supporting means for materials of varying widths, baffle means dividing the casing into a plurality of compartments each of which contains a plurality of the layers, means to feed air through the compartments and along the layers, said baffle means having openings for the carrier bars and other openings for the movement of the material from one to another of the compartments, and relatively slidable plates between the bars and also between the casing walls and the bars to close the said openings according to the width of the material to avoid unintended flow of air through the same, the opening for the material being relatively narrow, and a guide being provided to facilitate movement of the material through the said opening.
7. A tentering and drying machine including a casing, means therein supporting a material in a plurality of spaced layers, said means including carrier bars in proximity to opposite walls of the casing, said bars being movable toward or away from each other for adjustment of the supporting means for materials of varying widths, baffle means dividing the casing into a plurality of compartments each of which contains a plurality of the layers, means to feed air through the compartments and along the layers, said baffle means having openings for the vertical bars, said baffle means extending in parallelism to said layers and having an offset portion, said offset portion having an opening for the movement of the material from one compartment to another, and telescopic closure means for the openings to adjust the same according to the width of the material and prevent unintended flow of air through the openings.

In testimony whereof I affix my signature.
CHARLES C. KENYON.
